MICROPHONIC RELAY ASSEMBLY

Samuel F. Lybarger, Pittsburgh, Pa., assignor to
E. A. Myers & Sons, Pittsburgh, Pa., a partnership
consisting of Edward A. Myers and Edwin
J. Myers

Application March 19, 1934, Serial No. 716,255

5 Claims. (Cl. 179—171)

This invention relates to telephonic hearing appliances, and more particularly to a microphonic relay assembly devised for use in a portable ear-phone system of the type employed by the deaf to increase their hearing.

It is the common practice to employ in such system microphonic relays of the carbon granular type, which are a form of relay, as is well known in the art, in which a quantity of carbon globules loosely disposed between a pair of vertically disposed conductor plates is utilized to control the flow of a current therethrough in response to the movement of one or both of such plates. There are chiefly two different kinds of these relays, as microphonic transmitters and microphonic amplifiers or boosters as the latter are frequently called, and it is the latter of these toward which this invention is more particularly directed, although it is not necessarily so limited.

As customarily constructed these relays will function properly only when the plates thereof are maintained in a substantially vertical position. While a certain departure from such position is permissible depending on the particular construction used, if they are tilted in excess thereof, as they frequently are when used in ear-phone systems in the manner previously constructed, they either fail to function entirely or operate so inefficiently as to be very unsatisfactory and annoying to the user.

With this in mind it is an object of this invention to provide a microphonic relay assembly of this character which is designed for use in an ear-phone and adapted to substantially eliminate the difficulties to which reference has been made.

A more particular object is to provide a microphonic amplifier and battery assembly for use in a portable ear phone system which is adapted to be normally worn by the user in such a way that the amplifier is maintained in the proper position for its most efficient operation at all times.

Another object is to provide a unit of this nature which is simple and sturdy of construction, as well as relatively inexpensive to manufacture and exceptionally easy and convenient to use.

These and other objects, as well as the various other novel features and advantages of the invention, will be apparent when the following detailed description is read in conjunction with the accompanying drawing of which Fig. 1 is a view partly in elevation and partly in section of a battery unit and microphonic amplifier assembly constructed in accordance with the invention;

Fig. 2 an end elevation of the same assembly; Fig. 3 a diagrammatic view of the carbon globules and associated conductor plates of an amplifier such as shown in Fig. 1, illustrating such parts when disposed at right angles to the horizontal or their most effective operating position; Fig. 4 a view similar to Fig. 2 but showing the conductor plates tilted above their horizontal diameter in excess of 45°; Fig. 5 a view indicating the position which one of the units of the type contemplated by the invention frequently assumes when being used; and Fig. 6 a schematic view illustrating in full and dotted lines various positions in which the unit may be disposed in normal service.

Referring to Figs. 1 and 2 a microphonic booster relay of the type contemplated by this invention is illustrated which comprises a cup-shaped open-faced housing 1 within which, adjacent the rear wall thereof, there is arranged an electromagnet 2 of suitable design and construction. Directly in front of such magnet a flexible diaphragm 3 is provided which is held in place by a cover 4 threadably mounted on the open end of the housing 1. In the center of this diaphragm, adjacent the core 6 of the electromagnet 2 and operatively spaced therefrom, an armature 5 is secured. On the opposite side of such diaphragm a carbon disc 7 is mounted, being arranged for movement in a recess 8 in the cover 4 and adapted to form a movable wall at the inner end, of a chamber 9 formed by an opening 11 in the center of such cover. This chamber is utilized to house a quantity of carbon globules 12 which are arranged loosely therein and the cover which is made of dielectric material is made sufficiently thick to provide the proper space for such globules; while the space between the cover and disc 7 is made sufficiently small to prevent the globules escaping between it and the cover.

At the outer end of the opening 11 in the cover 4 there is provided a normally fixed carbon disc 14 which is removably held in a recess 13 by spring clip 15 to facilitate the assembly of the carbon globules. This clip 15 is also utilized as a terminal for a current-conducting circuit, not shown, which extends through the carbon globules 12 to the inner disc 7. Secured to a base support 16 on which the housing 1 is mounted on the bottom of this base there is mounted a pair of terminals 17 for connecting the booster to the cooperating terminals 20 of a battery or battery container 18, while on its top adjacent the relay a second set of terminals 21 is provided for conveniently connecting the booster in an ear-phone

circuit 22 as shown in Fig. 5. These terminals of course are suitably connected to the proper elements of the booster and detailed description thereof is deemed unnecessary.

5 The difficulty encountered in the use of a booster or relay of this nature in an ear-phone circuit, as referred to hereinbefore, is that the carbon globules 12, as shown in Fig. 4, fall away from one of the conductor plates 7 or 14 if the device 10 is permitted to tilt about the horizontal diameter of such plates, and reduce the effectiveness of the instrument in substantially the same ratio that the area of contact between such elements, is thereby reduced, and if tilted too far the circuit 15 is broken entirely rendering the relay completely inoperative.

To eliminate this difficulty in accordance with this invention a support 18 is provided for the relay which is adapted to be worn parallel with the front or back of the wearer's body and the relay mounted on such support with its carbon granular engaging plates 7 and 14 disposed as shown in Fig. 1 at right angles to the body-engaging surfaces of this support. Consequently as 20 most body movements are in the plane of the plates when so supported, the area of contact between them and the carbon globules is maintained in substantially the proper position for maximum effectiveness in operation at all times 25 independently of whatever the degree of body movement may be. As a further feature of the invention the battery employed for operating the hearing system in which the booster is used is employed as the support for the booster. Toward 30 this end, the battery or battery container on which the booster may be mounted as shown in Figs. 1 and 2 is made in a wafer-like manner and preferably so designed that it can be conveniently placed in a person's pocket as shown 35 in Fig. 5 or attached to the front of his or her clothing, being of course equipped with suitable 40 terminals 20 for receiving the booster. Such a unit has the further advantage that it can be laid on its side on a table or the like in the most 45 stable position of rest when not being worn by the user as indicated in Fig. 6, or tilted therefrom about its major axis without disturbing the area of contact which the carbon globules 12 maintain with both plates 7 and 14, such being 50 the equivalent of rotating the plates about their own axis.

According to the provisions of the patent statutes, I have explained the principle and mode of operation of my invention, and have illustrated 55 and described what I now consider to represent its best embodiment. However, I desire to have it understood that, within the scope of the appended claims, the invention may be practiced otherwise than as specifically illustrated and described.

I claim:

1. In combination, a microphonic relay comprising an electromagnet, a pair of spaced relatively movable conductor plates disposed adjacent said magnet, an armature disposed in the field of said magnet and connected to one of said plates for movement therewith, a quantity of granular current-conducting material loosely arranged between said plates to be influenced by the movement thereof, a flat faced support for said relay adapted to be worn by a person with the surface thereof bearing against the wearer's body, and

means for mounting said relay on said support with said plates disposed at right angles to the said body-contacting face.

2. In combination, a microphonic relay comprising an electromagnet, a pair of spaced relatively movable parallelly disposed conductor plates arranged adjacent said magnet, an armature connected to one of said plates for movement therewith in the field of said magnet, a quantity of granular current-conducting material loosely arranged between said plates, a support for said relay adapted to be worn by a person with a definite surface thereof bearing against the wearer's body, and means for mounting said relay on said support in such a manner as to positively maintain said plates at right angles to the body-contacting surface of the support.

3. In combination, a microphonic relay comprising an electromagnet, a pair of spaced relatively movable parallelly disposed conductor plates arranged adjacent said magnet, an armature connected to one of said plates for movement therewith in the field of said magnet, a quantity of granular current-conducting material loosely arranged between said plates, a flat faced support for said relay comprising a battery container adapted to be worn by a person with the surface thereof bearing against the wearer's body, circuit-making terminals on said relay and cooperating terminals in said support adapted to receive said relay terminals and maintain said plates at right angles to the body-contacting face of said battery container.

4. In combination, a microphonic amplifier comprising an electromagnet, a pair of spaced relatively movable parallelly disposed conductor plates arranged adjacent said magnet, an armature connected to one of said plates for movement therewith in the field of said magnet, a quantity of granular current-conducting material loosely arranged between said plates, a housing for said aforementioned relay elements, current-conducting terminals for said relay mounted on said housing, a battery adapted to be worn by a person with a surface thereof definitely bearing against the wearer's body, and circuit-making terminals in said battery for detachably receiving the terminals on said relay and mounting the conductor plates of said relay at right angles to the body-contacting surface of the battery.

5. In combination, a microphonic amplifier comprising an electromagnet, a pair of spaced relatively movable parallelly disposed conductor plates arranged adjacent said magnet, and armature connected to one of said plates for movement therewith in the field of said magnet, a quantity of granular carbon loosely arranged between said plates, a housing in which said relay parts are mounted, a base to which said housing is secured, terminals on said base for connecting said relay to a source of current supply, other terminals on said base for connecting the relay in an ear-phone circuit, a wafer-shaped battery designed to be worn against the front or back of a person's body and maintained parallel therewith, and cooperating terminals in said battery for receiving and engaging the battery terminals on said relay base and maintaining the plates of said relay at right angles to the body-contacting surface of said battery at all times.
